HAND BRAKE

Percy B. Camp, Maywood, and Herbert E. Bartsch,
Chicago, Ill., assignors to Universal Railway
Devices Company, a corporation of Delaware

Application April 8, 1943, Serial No. 482,272

9 Claims. (Cl. 74—432)

This invention relates to brakes for railway cars, and more particularly to brake shafts and to the method of manufacturing same.

One of the objects of the invention is the provision of a new and improved brake operating shaft that is fabricated from a plurality of parts so arranged as to greatly reduce the cost of production without decreasing the margin of safety.

Another object of the invention is the provision of a new and improved brake shaft assembly composed of a plurality of parts that may be easily and readily put together to form a unitary structure.

A further object of the invention is the provision of a new and improved shaft for railway brakes that is a drop forging on which is mounted an integral pinion and ratchet wheel in the form of a malleable casting.

A still further object of the invention is the provision of a new and improved brake shaft assembly that is strong and durable, is inexpensive to manufacture, and that may be easily and readily assembled.

Other and further objects and advantages of the invention will appear from the following description, taken in connection with the accompanying drawings in which

Fig. 1 is a side elevation of a portion of the end of a car with a brake in position thereon, and parts broken away;

Fig. 2 is a modified form of combined shaft, pinion and ratchet wheel assembly;

Fig. 3 is a section on the line 3—3 of Fig. 2;

Fig. 4 is an exploded view in perspective of a brake shaft, pinion and ratchet wheel assembly showing a modified form of construction; and

Fig. 5 is a longitudinal section of the form of construction shown in Fig. 4 when the same is assembled.

In the manufacture of railway equipment of various kinds, efforts are being made to reduce the cost of production without reducing the quality of the article or of the mechanism on which the article or equipment is employed.

It is common practice to employ a cast steel brake shaft having integral therewith the brake drum operating pinion and ratchet wheel as a unitary structure, but this is more or less expensive and there is the ever present danger that the steel casting may have one or more blow holes that may not be detected until failure and a possible accident occurs. For, in applying a hand brake on a freight car the brakeman must stand on a small platform attached to the end of the

car, and in this position he must exert considerable force to turn the brake wheel in applying the brakes. Any sudden failure of the mechanism, therefore, is likely to throw him off balance and may cause a serious accident.

The present invention seeks to remedy these difficulties by the use of a drop forged brake shaft which increases the margin of safety over a steel casting and the use of a brake drum operating pinion and ratchet wheel of malleable casting, which will materially reduce the cost of production.

Referring now to the drawings, the reference character 10 designates the end of a railway car to which is rigidly secured the brake housing 11 within which the brake operating mechanism, designated generally by the reference numeral 12, is secured. This mechanism is shown in detail in our Patent No. 2,318,569 issued May 4, 1943, for Hand brake, and of which this is a continuation in part.

Since a disclosure of the details of the brake operating mechanism is not necessary to an understanding of the invention, it is not thought necessary to illustrate and describe the same further than to state that this mechanism comprises a brake shaft 13, a squared tapered portion 14 on which the brake wheel 15 is secured, as by means of a nut 16 on the threaded end 17 of the brake shaft 13. Inwardly of the brake wheel 15 is a journal portion 18 which engages a bearing 19 secured in the outer wall of the housing. On the central portion of the brake shaft 13 is an enlarged squared portion 21, and inwardly of the latter is a reduced cylindrical portion 22. The shaft 13 thus far described is a unitary structure, and since, in winding up the brake chain 20, considerable force must be applied by the brakeman, it is necessary, in order to avoid accidents, that the brake shaft 13 be rugged, with no danger of fracture during the application of the brakes. For that reason the shaft is forged, thereby avoiding danger of hidden weaknesses, as would be possible were the shaft of cast steel.

Mounted on the inner end of the shaft 13 is a combined ratchet wheel 23 and pinion 24. This pinion is adapted to engage the brake drum gear 25 for rotating the brake drum in the usual manner. The ratchet wheel 23 is adapted to be engaged by a pawl 26, which prevents backward rotation of the shaft 13 while the brakes are being applied. The combined pinion 24 and ratchet wheel 23 is provided with an axial opening 30, which is enlarged at its outer end and

squared to conform to the shape of the squared portion 21 on the shaft 13.

The inner end of the combined ratchet and pinion is extended inwardly beyond the teeth of the pinion to form a mask 27 for the teeth, and this mask constitutes a journal for the brake shaft assembly. It is journaled in a bearing 28 formed in the inner wall of the brake casing, as shown in Fig. 1 of the drawings. In order to hold the pinion and ratchet wheel in position on the brake shaft 13, the inner end of the opening 30 is flared or beveled, as at 40, and the end 22 of the brake shaft is peened over or upset to engage the tapered wall of the mask 27, as shown in Fig. 1, to thereby hold the parts firmly on the shaft 13.

The combined pinion and ratchet structure is a malleable casting. By making this portion of the assembly a malleable casting and separate from the shaft, the cost of production of the unit is materially reduced without reducing the margin of safety, so far as the hazard to the operator is concerned. It will be appreciated that even though a tooth or ratchet fail on the operating mechanism, the operator will still have the wheel 15 in his grasp, so that there is not so much danger of his falling from the platform; whereas, if the shaft 13 should break off between the wheel and the casing during the application of the brake, the chances are very great that the operator would fall from the car and a serious accident would probably result. The likelihood of failure of the malleable casting, however, is very remote.

The construction shown in Figs. 2 and 3 differs principally from that shown in Fig. 1 in that the brake drum operating pinion is integral with the shaft. In this form of construction the shaft 13^a is provided with what may be termed teeth 29, each of which is arranged substantially radial on its forward side, as at 31, and more or less inclined, as at 32, on its opposite side. These teeth are adapted to engage corresponding recesses in a ratchet wheel 33, as shown more clearly in Fig. 2. The ratchet wheel 33 engages the shaft 13^a and teeth 29 by a press fit, and the ratchet wheel is provided on its outer hub portion with reinforcing ribs 34 which extend around said recesses, as shown more clearly in Fig. 3. The shaft 13^a is provided adjacent its inner end with a pinion 35, and inwardly of the pinion is the journal 36. In this form of construction the teeth 29, pinion 35, and journal 36 are all integral and are drop forged. The ratchet wheel 33 is a malleable casting, as in the previous construction.

In Figs. 4 and 5 is shown a modified form of construction, which, however, is the preferred form and is very similar to that shown in Fig. 1. It comprises a shaft 13^b having a tapered squared portion 38 on which the brake wheel 15 is adapted to engage, as in Fig. 1, and the outer end of the shaft is screw-threaded, as at 39, for receiving a nut for holding the brake wheel in position on the squared portion 38. The shaft is provided with a journal 41 inwardly of the squared portion 38, and inwardly of the journal 41 is a collar or shoulder member 42; and inwardly of the shoulder 42 is an enlarged, substantially rectangular, portion 43, having the corners 44 flattened, as shown in Fig. 4. The shaft extends inwardly beyond the rectangular portion 43 and is cylindrical, as shown at 45. The shaft 13^b, together with the journal 41, collar or shoulder 42, and the rectangular portion 43 and shaft end 45, are all integral and are adapted to be drop forged, as in the previous construction.

Adapted to be mounted on the shaft 13^b is a ratchet wheel 46, a pinion 47, and a journal 48. The ratchet wheel 46, pinion 47, and journal 48 are a unitary construction having an axial opening 50. This unit is a malleable casting. The outer face of the ratchet wheel 46 is provided with a deep recess 49, which is substantially rectangular in form having the corners 51 which correspond to the corners of the rectangular member 43 and are adapted to receive the same. Substantially midway between the sides of the rectangular opening 49 are semi-circular cut-out portions 52 in three of these sides, and these cut-out portions are provided to relieve the stresses due to the cooling after the casting operation. On the fourth side the cut-out portion 53 is of a different form, and is not of sufficient depth to permit the parts to be assembled in any but the proper manner. In other words, the corners 44 cannot be made to engage in the recesses 52 and 53, but will engage only in the corners 51 of the recess 49. This arrangement insures the correct assembly of the parts.

The inner end of the opening 50 is counter-bored, as at 55, and provided with tapering walls 56 so that when the parts are assembled the end 45 of the shaft 13^b may be swaged, as at 57, for holding the parts in assembled relation.

It will thus be seen that in all forms of the device the brake shaft assembly is composed of two parts, and that the shaft constituting one of those parts is an essential and important element of the brake operating mechanism, and is forged; while the ratchet wheel, or ratchet wheel and pinion, which constitutes the other part of the assembly, is a malleable casting. The cost of forging the shaft, pinion and ratchet wheel as a unitary structure would be prohibitive, but by employing a malleable casting on a forged shaft a strong and rugged assembly is produced at a saving in the cost of work and material.

An important feature of the described embodiments of our invention is the provision of certain safeguards against inoperativeness that might arise from separation of the interlocked parts. It is to be borne in mind that a brake mechanism of the character described on a railway car is intended to serve for years without special attention, and should be proof against structural failure.

In all of the described forms of the invention a hollow body having a portion shaped to provide ratchet teeth embraces a shaft to move therewith in a unitary manner, and positive means are provided to prevent three kinds of relative movement between the hollow body and the shaft—the three movements being relative rotation, relative axial movement in one direction, and relative axial movement in the opposite direction. Relative axial movement in one direction between the hollow body and the shaft may mean, of course, simultaneous movements of both parts in opposite directions, movement of the hollow body in one direction while the shaft is stationary, or movement of the shaft in the opposite direction while the hollow body is stationary.

The prevention of relative rotation between the hollow body and the shaft is accomplished preferably in the manner described, that is, by giving the hollow body a non-circular interior configuration to fit over a complementary non-circular portion of the shaft. Obviously, however, other expedients may be employed to prevent relative rotation.

Relative axial movement between the hollow body and the shaft in one direction is prevented in a positive manner by cooperating shoulders formed on the hollow body and the shaft, respectively. In practice this particular cooperation is provided by an enlargement on the shaft and a recess in the hollow body. Preferably both the enlargement and the recess are tapered for what may be termed a wedging fit in the manner described to favor rigid interconnection.

In all three of the described forms of the invention means separate and apart from the hollow body and shaft serve as obstacles to prevent relative axial movement between the hollow body and the shaft in the opposite relative direction. Thus, in Fig. 1 the housing or casing for the brake mechanism provides in effect thrust bearings, one of which rotatably embraces the shaft, the other thrust bearing rotatably embracing the hollow body. The casing, therefore, serves to prevent both axial movement of the shaft away from the hollow body and axial movement of the hollow body away from the shaft, both of these movements being regarded as in the same relative direction.

In Fig. 1 the peening or swaging 40 at the end of the shaft is the normal means for preventing the axial movement of the shaft and the hollow body in the above-mentioned opposite relative direction. The inherent safety feature resides in the fact that in the event such peening or equivalent expedient fails to prevent separation of the two parts the casing itself will serve as positive means to prevent such degree of separation as to make the brake mechanism inoperative.

The third embodiment shown in Figs. 4 and 5 is closely similar to the first embodiment with respect to the inter-relation of the parts. The second form of the invention shown in Figs. 2 and 3, however, is somewhat different in construction but, nevertheless, provides the same inherent feature since the right-hand bearing for the shaft would prevent axial movement of the shaft away from the hollow body, while, on the other hand, the brake drum gear 25 (Fig. 1) lies in the path of the hollow body of Fig. 2 to serve as an obstacle limiting axial movement of the hollow body out of engagement with the shaft.

It is thought from the foregoing, taken in connection with the accompanying drawings, that the operation and construction of our device will be apparent to those skilled in the art, and that changes in size, shape, proportion and details may be made without departing from the scope and spirit of the appended claims.

We claim as our invention:

1. In a railway brake having a casing and brake operating mechanism within said casing, a brake shaft assembly comprising a shaft journaled within said casing and having an enlarged angular portion within said casing, a combined pinion, journal and ratchet wheel telescoped on said shaft and having a recess for receiving said angular enlargement for causing the combined pinion, journal and ratchet wheel to rotate with said shaft, the inner end of said shaft being swaged to lock the combined pinion, journal and ratchet wheel on the shaft.

2. In a railway brake of the character described, a brake shaft assembly comprising a shaft having a longitudinally tapered non-circular portion, a one-piece hollow body forming a combined pinion and ratchet wheel, the hollow

interior of said body being of longitudinally tapering non-circular configuration complementary to said portion of the shaft to prevent rotation of the body relative to the shaft and being rigidly interlocked in a taper fit with said portion to prevent in a positive manner movement between the hollow body and the shaft in one relative direction, and means interlocking the hollow body and shaft against movement in the opposite relative direction.

3. In a brake operating mechanism, a brake shaft having a journal portion, a ratchet wheel rotatable with said shaft and a combined pinion and journal to rotate with said shaft, means for causing said pinion and journal to rotate with said shaft, means interlocking said shaft and combined pinion and journal to prevent movement therebetween in one relative direction, and a casing rotatably supporting said two journals and providing obstacles to movement of said shaft and combined pinion and journal in the opposite relative direction.

4. In a railway brake of the character described, a brake shaft and body embracing said shaft to constitute therewith a shaft assembly, said body having a portion forming ratchet teeth, said body and shaft having non-circular portions in mutual engagement to cause the body to rotate with the shaft, shoulders on said body and shaft, respectively, cooperating in abutment to prevent axial movement therebetween in one relative direction, said body and shaft having parts, respectively, in mutual engagement to resist axial movement therebetween in the opposite relative direction, and means apart from said shaft assembly providing obstacles in the path of said body and in the path of said shaft, respectively, to limit axial movement therebetween in said opposite relative direction in the event said mutual engagement of the parts fails.

5. In a railway brake of the character described, a brake shaft having a tapered non-circular enlargement, a body embracing said shaft to constitute therewith a shaft assembly, said body having a tapered non-circular recess for engagement by said enlargement to cause the body to rotate with the shaft and to prevent movement between the shaft and the body in one relative direction, said body having a portion forming ratchet teeth, and means interlocking said body and shaft against axial movement therebetween in the opposite relative direction.

6. In a railway brake of the character described, a brake shaft, an integral pinion and ratchet unit embracing said shaft to constitute therewith a shaft assembly, said unit and shaft being interlocked by non-circular parts integral therewith to cause the unit to rotate with the shaft, shoulders on said unit and shaft, respectively, in abutment to prevent axial movement therebetween in one relative direction, and means rotatably supporting said shaft assembly, said supporting means having portions positioned as obstacles in the paths of relative movement of said unit and said shaft, respectively, to limit axial movement therebetween in the opposite relative direction.

7. In a railway brake of the character described, a brake shaft having a tapered non-circular enlargement, an integral pinion and ratchet unit mounted on said shaft to constitute therewith a shaft assembly, said unit having a tapered non-circular recess complementary to said enlargement and in engagement therewith both to cause rotation of the unit with the shaft and to

prevent axial movement therebetween in one relative direction, means interlocking said shaft and unit against axial movement therebetween in the opposite relative direction, said means rotatably supporting said shaft assembly, said supporting means having portions positioned as obstacles in the paths of relative movement of said unit and said shaft, respectively, to limit axial movement therebetween in the opposite relative direction.

8. In a railway brake of the character described, a brake shaft having a journal portion, a body embracing said shaft to constitute therewith a shaft assembly, said body having a ratchet portion and a journal portion, shoulders on said body and shaft, respectively, in mutual abutment to prevent axial movement between the shaft and the body in one relative direction, and means cooperating with said shaft assembly to rotatably support said journal portions and to limit axial

movement between the shaft and body in the opposite relative direction.

9. In a railway brake of the character described, a brake shaft having a journal portion, a body embracing said shaft to constitute therewith a shaft assembly, said body having a ratchet portion and a journal portion, shoulders on said body and shaft, respectively, in mutual abutment to prevent axial movement between the shaft and body in one relative direction, means interlocking the shaft and body to prevent axial movement therebetween in the opposite relative direction, and means providing thrust bearings for said journal portions to rotatably support the shaft assembly and to limit axial movement between the shaft and body in said opposite direction in case of failure of said interlocking means.

PERCY B. CAMP.
